UNITED STATES PATENT OFFICE

JOSEPH W. FARR, OF OAK PARK, ILLINOIS

SELF-FURRING LATHING NAIL

Application filed July 11, 1928. Serial No. 291,893.

My present invention relates to the provision of what may be termed a self furring lathing nail for metal lathing. It is necessary to space lathing, metal or otherwise, a sufficient distance from the structure which supports the same to permit of the anchorage of the plaster being forced through the slots between the wood lath or the perforations or interstices in the metal lath, as the case may be. This spacing of the lath from the studding or other structural portion of the building which is to be plastered is generally attained by nailing to the structural portions of the building relatively narrow strips of wood called furring, and nailing the lath in turn to the furring. With metal lath nailed to furring strips in particular the slight displacement of the structural portions of the building through expansion and contraction and divers other causes effects the metal lath and the plaster carried thereby so as almost invariably to show in a short time on the completed structure the location of the furring strips.

As will hereafter be seen, the structure embodying my invention provides a slightly flexible spacing element, or furring, between the structural portions of the building and the lathing and plaster whereby a slight movement of the structural elements of the building will not have any effect either upon the metal lath or plaster carried thereby.

It will further appear that my structure is extremely simple both in manufacture and in application and will secure substantial economy in the labor necessary for installation.

I secure the foregoing objects and results by means of the structure illustrated in the accompanying drawing in which—

Fig. 1 is a perspective elevation of a self furring lathing nail embodying my invention; and

Fig. 2 is a schematic section of studding or other structural elements of a building to which metal lathing is secured and from

which it is spaced by means of nails embodying my invention and the relation of the plaster thereto.

Similar reference characters refer to similar parts throughout the respective views.

I prefer to employ a wire, wrought iron, or otherwise pliable nail 3 transversely of which are secured, by pressing through central perforations, or in any other desired manner, plates 4 and 5 spaced a suitable distance from each other to secure the necessary furring functions and from the head 6 of the nail a sufficient distance to permit of the head end of the nail being bent over upon and dependably securing the lathing 7 upon or adjacent the upper or outer plate 5.

In Fig. 2 I have shown the metal lathing as consisting of a woven or reticulated structure, but, as is obvious, any of the forms of perforate metal lathing may be employed equally well with my self furring lathing nail.

In Fig. 2 the studding or other structural elements of the building which hold the lath and plaster are schematically shown and designated by the character 8. The nails 3 are driven into these structural elements until the inner plates 4 abut the surfaces thereof. The spaces between the plates 4 and 5 perform the function of furring and the lathing 7 is placed over the heads of the nails and upon the outer surfaces of the plates 5. The head end 6 of the nail which extends beyond the plate 5 is then bent over upon the lathing and the plaster 8 is applied, a portion of which is forced through the perforations in the lathing to form the anchorage 9. With this construction the ordinary and inevitable slight shifting of the structural elements of the building may occur without in any way disturbing or putting stress upon the lathing and plaster.

It should be further noted that my self furring lathing nail has important sound deadening properties as vibrations cannot pass along the nails as readily as they do.

through the structural portions of the building and the furring.

It is also obvious from the foregoing description taken in connection with the illustration that the metal lathing may be very readily and economically put and secured in position by the lathing nail herein described.

Having described my invention what I claim as new and desire to secure by Letters Patent is—

- 10 1. A self furring lathing nail for metal lathing consisting of a nail provided with plates disposed transversely of said nail and in spaced relation with each other, the outer plate being of such size and so spaced from and related to the head end of said nail as to permit the nail head of said nail to be clinched down in any direction upon or adjacent said outer plate.
- 15 2. A self furring lathing nail comprising a standard form of nail transversely whereof are forced in spaced relation to each other and the ends of said nail, centrally perforate plates, the plate nearest the head of said nail being of such length and breadth as to provide an adequate support for the lathing and co-operate with the outer end of said nail when bent in any direction in holding said lathing in place.
